SOLE FITTING

William R. Bolton, Chicago, Ill., assignor to
 United Shoe Machinery Corporation, Paterson,
 N. J., a corporation of New Jersey

Application April 24, 1934, Serial No. 722,161

4 Claims. (Cl. 12—146)

This invention relates to sole fitting and is herein illustrated and described with reference to a method of operating upon double-lipped insoles, and also to a sole which has been thus operated upon.

Insoles are commonly provided with an outer lip formed by an edge cut and an inner lip formed by a face cut in the sole. These lips extend forwardly from about the breast line of the sole and are separated from each other by a relatively small width of uncut sole material, known as the "between substance". The lips are subsequently turned up and secured to each other back to back to form a rib. This operation is performed by a lip-setting machine which, for example, may be of the type disclosed in United States Letters Patent No. 1,213,770, granted January 23, 1917, upon an application of Albert E. Johnson.

In order to improve the manufacture of such insoles, the present invention comprises a method which consists in providing a double lipped insole and removing material from the lips thereof at a locality near one of the ends of the lips to form notches which facilitate the entering beneath said lips of lip-raising instrumentalities; and preferably, simultaneously with the making of the notches, making cuts connecting said notches to ensure that, irrespective of the widths of the lips, the ends of the lips shall be severed from their outer edges to their points of attachment to the insole. In carrying out the method, a novel product is produced, namely a double lipped insole having the above described notches and preferably also the cuts which connect the notches.

The improved machine disclosed but not claimed herein constitutes the subject matter of my divisional application Serial No. 30,490, filed July 9, 1935.

Referring now to the accompanying drawing:

Fig. 1 is a view in perspective illustrating the step of forming cuts in the lips of an insole by a machine;

Fig. 2 is a view in perspective of a knife shown in Fig. 1; and

Fig. 3 is a plan view of the heel end of an insole which has been operated upon by the machine shown in Fig. 1, illustrating the manner in which lip-raising instrumentalities are entered beneath the lips.

In Fig. 3 is shown a heel end of a double-lipped insole S having an outer lip L and an inner lip L'. Each of the lips begins at a point slightly to the rear of the breast line and ex-

tends continuously around the shank and fore-part of the insole. In accordance with the improved method, material is removed from one end of the outer lip L to form a U-shaped notch N, and material is similarly removed from the inner lip L' to form a U-shaped notch N'. Connecting the notches N and N' and extending through the between substance is a straight cut C. The notches N and N' and the cut C may conveniently be made by a knife such as that shown in Fig. 2 in a machine of the type shown in Fig. 1, which will presently be described in detail. At the other end of the lips L and L', there may be conveniently formed a straight cut C' to mark definitely the termination of the lips. The cuts C and C' are usually made at about the heel-breast line of the sole. After these operations have been performed upon the sole S, the lips L and L' are raised and secured together by cement or stitching to form a ridge. The raising of the lips may conveniently be accomplished by the use of a machine such as that disclosed in the above-mentioned Letters Patent No. 1,213,770, which (as shown in Fig. 3 of that patent) is provided with a pair of plow-like members for engaging the under surface of the lips to turn the lips up. The notches N and N' facilitate the entrance of these plow-like members beneath the lips. As shown in Fig. 3, one of the plows 10 is in the process of entering beneath the lip L and the other plow 8 is in the process of entering beneath the lip L'. As the sole is fed, the plows advance progressively beneath the lips and emerge at the cut C'.

It will be noted that, according to the method as so far described, the cuts N, N' and C are formed in an insole which has already been channeled. It may sometimes be convenient however, and the result will be the same, to make these cuts in an insole blank before the lips L and L' are formed by the channeling operation.

In Fig. 1 are shown the operating instrumentalities of a machine for forming the above-mentioned notches and cuts. This machine consists of a frame 12 having a raised portion 14 which serves as a work support. The heel portion of the sole S is centered upon the work table 14 by a pair of gages 16 which are controlled by mechanism similar to that disclosed in United States Letters Patent No. 1,113,544, granted October 13, 1914, upon an application of Miller Cook, Jr. As disclosed in that patent, the centering gages are mounted for transverse movement with respect to the center line of the machine, being connected by gearing in such

manner as to insure that both gages are always at an equal distance from the center line and being urged toward the center line by a spring. For a more complete understanding of the mechanism for centering the gages 16, reference may be had to the above-mentioned Letters Patent No. 1,113,544. Adjustably mounted on the work table 14 is a gage 18 for engaging the rear end of the sole. A bridge member 20 serves to hold the sole down against any tendency of the gages 16 to raise it. The machine is provided with a knife 22 having a cutting edge 24 which is shaped to form the notches N and N' and the straight cut C. The machine is also provided with a knife 26 having a straight edge to form the cut C'. The knives 22 and 26 may conveniently be mounted and operated in the same manner as the knives disclosed in the above-mentioned Letters Patent No. 1,113,544.

20 In the operation of the machine, the heel end of the sole S is passed beneath the bridge 20 and between the gages 16 until the rear end of the sole abuts the gage 18. Upon starting the machine, the knives 22 and 26 descend and 25 make their respective cuts, the position (forwardly or rearwardly) of which cuts is determined by the adjustment of the gage 18. The knives may be lowered and raised continuously, or, if desired, the machine may be provided with 30 a mechanism for stopping it automatically after each cycle of movement of the knives.

Having described the invention, what is claimed as new and desired to be secured by Letters Patent of the United States is:

1. That improvement in methods of fitting insoles which consists in providing a double lipped insole and removing material from the lips thereof at a locality near one of the ends of the lips to facilitate the entering beneath said lips of lip-raising instrumentalities. 5
2. That improvement in methods of fitting 10 soles which consists in removing material from the inner and outer lips of a double lipped insole to provide notches defining the beginnings of said lips, entering lip raising instrumentalities in said notches, and operating said instrumentalities to raise said lips. 15
3. A double lipped insole having, in the vicinity of the heel breast line, notches in the inner and outer lips respectively and a cut connecting 20 the notches and extending across the between substance to define the beginnings of the lips and to facilitate the entrance of lip raising instrumentalities beneath the lips. 25
4. A double lipped insole having, in the vicinity of the heel breast line, notches in the inner and outer lips respectively to define the beginnings of the lips and to facilitate the entrance of lip raising instrumentalities beneath the lips. 30

WILLIAM R. BOLTON.
